CHARLES H. STOUT, OF NORTH ARLINGTON, AND JUAN CABALLERO, OF SOUTH ORANGE, NEW JERSEY.

AUTOMATIC PENCIL.

Application filed July 13, 1926. Serial No. 122,075.

The invention relates to automatic pencils and particularly to that type of pencil adapted to project and withdraw leads of two different colors or degrees of hardness.

5 The objects of the invention are to provide a pencil of this type which is extremely simple, cheap to manufacture and efficient in use. Multi-color automatic pencils at the present time are bulky and cumbersome, expensive to 10 manufacture and very easy to get out of order. Due to the fact that their leads are not properly supported they constantly break while being used. Another serious disadvantage is that the pencil has to be rotated a 15 number of times to withdraw one lead and project the other. In the pencils in use at the present time one is only able to use a very short lead and this necessitates renewing the leads very often, which is a considerable annoyance. The present invention is designed to overcome all of these faults. A pencil is 20 provided in which the leads are always well supported when in use. This is accomplished by providing novel means for projecting the 25 leads of either color so that they are always in exact line with the central axis of the pencil. Only a very slight rotation is necessary to change from one lead to the other and one is able to use a substantially long lead.

30 The pencil being formed almost entirely of standard tubing very little machine work is required in making and assembling and this makes for great economy in manufacturing.

Other objects and advantages will become 35 apparent as this specification proceeds. For a clear understanding of the invention, drawings, in which are illustrated one embodiment, are provided. Referring to said drawings:

40 Fig. 1 is a central longitudinal section, a fragment of the upper part being in elevation;

Fig. 2 is a cross sectional view on a larger scale, taken on line 2—2 of Fig. 1;

45 Fig. 3 is a detail elevation showing the outer tube in elevation and the casing in section;

50 Fig. 4 is a detail perspective view of the inner spirally grooved tube with a portion of the guide tube projecting from the upper part thereof,

Fig. 5 is a detail perspective view partly in section of the guide tube and lead carriers,

Fig. 6 is a detail elevation of one of the lead supporting tubes, and,

55 Figs. 7 and 8 are detail sections, on a large scale, illustrating the means by which the lead is carried to the central axis of the pencil. These sections are taken on the line 7—7 of Fig. 1, showing the guide pin just entering 60 the helical slots.

65 Referring again to the drawings the reference numeral 10 indicates the outer casing which may be made of rubber, celluloid, or any suitable material. Within the casing are 70 two tubes 11 and 12 telescoped one within the other. Each of these tubes is provided with a pair of oppositely disposed spiral grooves or slots which cooperate with each other so that the leads are projected or withdrawn 75 when the tubes are rotated relative to each other.

80 The outer tube 11, particularly illustrated in Fig. 3, has the lower spiral groove 13 and the upper spiral groove 14. These grooves 85 13 and 14 merge into annular grooves or slots 15 and 16, which are formed in a plane substantially at right angles to the central axis of the tubes and extend part way around the diameter of the tube. The pitch of the groove 13 is the reverse of that of the groove 14.

85 The inner tube 12, as shown in Fig. 4, is likewise provided with two spiral grooves 17 and 18 which merge into straightaway portions 19 and 20. The pitch of the grooves 17 and 18 is also oppositely disposed. The tube 12 is positioned within the tube 11 so that the annular grooves 15, 16 and 19, 20 are in line with each other and the grooves 13, 14 and 17, 18 are adjacent each other. The spiral 90 grooves 13, 17 and 14, 18 of their respective tubes are of reverse pitch to each other when the tubes are in position.

95 Pins 21 and 22 attached to lead carriers, which will be described hereinafter, cooperate with these two sets of grooves. In the position shown in Fig. 1, the pins 21, 22 are in the annular parts of the grooves. Thus it may be seen that if the tubes are rotated in relation to each other one of the pins 21, 22 100 will be forced downward, thus projecting its respective lead carrier and lead, and the

other pin will ride in the annular parts of the grooves. When the tubes are rotated in the opposite direction this lead carrier will be withdrawn and when its pin reaches the annular part of the groove the pin of the other lead carrier is in position to project that carrier.

Means are provided so that when pressure is applied to the extended lead, as it would be in writing, the lead is not forced back in the tubes. Secured in the outer casing 10 is a shouldered bushing 23. Resting between this bushing and the end of the tube 11 is a spring 24. The opposite end of the tube 11 is serrated at 25 and cooperates with serrations on the end of a bushing 26 which is secured, adjacent a shoulder 27, on the upper end of the tube 12. When the tubes are turned in relation to each other the serrations will readily ride over one another but when the lead has been projected a sufficient amount the spring 24 will cause the serrations to lock, and the lead cannot slip back when a light pressure is applied to its end, as in writing.

25 The lower end of the inner tube 12 is threaded at 28 to accommodate an internally threaded portion of the tip 29. The tip is of the usual formation and has the lead guide and support 30 at its extreme end. The pencil is operated by revolving the tip. The tip 29 being secured to the tube 12 will cause said tube 12 to turn in relation to the tube 11 when the tip is revolved, thus projecting or withdrawing the leads.

30 Inside the tube 12 is located another tube 31, which acts as a guide for the lead carriers and also as a magazine for the spare leads. This tube is particularly illustrated in Fig. 5. As shown it is provided at opposite sides with guides 32 in the form of longitudinally extending grooves or infoldings. Its lower end may be pressed together or as shown it may be closed by a plug or washer 33 so as to form a bottom for the lead magazine.

35 The lead carriers from which the pins 21 and 22 project slide in the guide grooves 32. These lead carriers might be constructed in numerous different ways and as illustrated, comprise long thin tubes 34, extending substantially the length of the body portion of the pencil. The pin 21 which cooperates with the annular grooves 15, 19 and the spiral grooves 13, 17 extends from and is secured to the intermediate part of one of the tubes 34, and the pin 22 which engages the annular grooves 16, 20 and the spiral grooves 14, 18, extends from and is secured to the upper part of the other tube 34.

40 Extending from and secured to the lower parts of the tubes 34 are pins 35 which are provided with offset portions 36. Secured on the outer ends of said pins 35 are short lead holders 37. When either of the leads are projected they are firmly supported at one end by the lead holder and at the other end

by the guide portion 30 of the pencil tip 29. The leads may be additionally supported by slotted members 38. The members 38, as illustrated, are formed of independent tubes but, if preferred they might be integral extensions from the guide tube 31.

45 In order that the leads be firmly supported so that there is no possibility of their breaking as soon as they are projected beyond the tip, when in use, it is very important that they be projected in a straight line, coincident with the central longitudinal axis of the pencil. As illustrated this is accomplished by varying the pitch of the spiral grooves 13, 17 and 14, 18. This is particularly illustrated in Figs. 7 and 8. Fig. 7 shows the position of the pin 21 or 22 just as it leaves the annular part of the grooves and enters the spiral part. At this time the leads would be approximately in the position shown in Fig. 1. Fig. 8 shows the position of the pin after the lead has been projected from the position of Fig. 1 to the top of the tip guide 30. The spiral grooves are so formed as to cause the lead carriers to turn upon their own axis, immediately after entering said grooves. This naturally causes the offset portions of the pins 35 to turn as a crank and swing the lead holders and leads to the center of the pencil as shown in Fig. 8. The offset portions of the pins are so proportioned that when one lead is in the center of the pencil there is no interference with the other lead or holder. When both leads are in their highest positions and the pins 21 and 22 are in the annular parts of the grooves they assume a position approximately that shown in Figs. 1 and 2.

50 The foregoing result might be accomplished in other ways, for instance, the guide portions 32 of the tube 31 might be extended down further and slots with offset portions cut therein to accommodate the pins 35. Thus if either of the leads were projected the pins 35 striking these offset portions of the slots would swing the leads and lead holders to the center of the pencil.

55 The upper end of the inner tube 12 is formed to accommodate the eraser holder 39 and eraser 40. The eraser holder 39 acts as a closure for the lead magazine. The eraser and top of the pencil is preferably covered by a cap 41 of any suitable nature.

60 While a preferred embodiment of the invention has been illustrated and described it is obvious that numerous changes in arrangements of parts and details of construction might readily be made by one skilled in the art, without departing from the spirit of the invention or the scope of the appended claims.

65 What we claim as new is:

1. An automatic pencil comprising, a pair of tubes, telescoped one within the other and having spiral grooves therein, the grooves in each tube having opposite pitches, and a

pair of lead carriers within the tubes cooperating with the grooves, the arrangement being such that when the tubes are rotated in one direction in relation to each other, one of the lead carriers will be projected forwardly and the other withdrawn and when the tubes are turned in the opposite direction the movement of the lead carriers will be reversed.

10 2. An automatic pencil comprising, a pair of tubes, telescoped one within the other, each tube having two spiral grooves of opposite pitch and assembled so that the adjacent grooves of each tube are of opposite pitch, 15 and a pair of lead carriers within the tubes cooperating with the grooves, the arrangement being such that when the tubes are rotated in one direction in relation to each other, one of the lead carriers will be withdrawn and the other projected forwardly and when the tubes are turned in the opposite direction the movement of the lead carriers will be reversed.

3. An automatic pencil comprising, a pair 25 of tubes, telescoped one within the other, each tube having two spiral grooves of opposite pitch, said spiral grooves terminating in annular grooves going part way around the diameter of the tubes in a plane substantially 30 at right angles to the longitudinal axis of the tubes, the adjacent grooves of each tube being of opposite pitch, and a pair of lead carriers within the tubes cooperating with the grooves, the arrangement being such 35 that when the tubes are rotated in one direction in relation to each other, one of the lead carriers will be withdrawn and the other projected forwardly and when the tubes are turned in the opposite direction the movement of the lead carriers will be reversed.

4. An automatic pencil comprising, a pair 40 of tubes telescoped one within the other, each tube having two spiral grooves of opposite pitch, said spiral grooves merging into annular grooves going part way around the diameter of the tubes in a plane substantially 45 at right angles to the longitudinal axis of the tubes, the adjacent grooves of each tube being of opposite pitch and the annular parts 50 of the grooves of each being in the same horizontal plane, and a pair of lead carriers having guide pins, the pin of one carrier cooperating with one set of grooves and the pin of the other carrier cooperating with the 55 other set of grooves, the arrangement being such that when the tubes are rotated in one direction in relation to each other, one of the lead carriers will be withdrawn and the other projected forwardly and when the tubes are turned in the opposite direction the movement 60 of the lead carriers will be reversed.

5. An automatic pencil comprising, a pair 65 of tubes, telescoped one within the other, each tube having two spiral grooves of opposite pitch, said spiral grooves merging into

annular grooves going part way around the diameter of the tubes in a plane substantially at right angles to the longitudinal axis of the tubes, the adjacent grooves of each tube being of opposite pitch and the annular 70 parts of the grooves of each tube being in the same horizontal plane, a pair of lead carriers having guide pins, the pin of one carrier cooperating with one set of grooves and the pin of the other carrier cooperating with 75 the other set of grooves, and guides for the lead carriers, the parts being so arranged that when the pin of one of the lead carriers is in the annular part of the grooves that lead carrier will not move longitudinally when the tubes are being rotated in relation to each other and the other lead carrier may be projected or withdrawn by rotation of the tubes.

6. An automatic pencil comprising, a plurality 80 of tubes one within the other, two of the tubes having spiral grooves therein, the grooves in each tube being of opposite pitch, a pair of lead carriers within the tubes cooperating with the spiral grooves, 85 the arrangement being such that when the tubes are rotated in one direction in relation to each other one of the lead carriers will be withdrawn and the other projected forwardly and when the tubes are turned in 90 the opposite direction the movement of the lead carriers will be reversed, and means to insure either of the lead carriers always being projected in a line coincident with the central axis of the tubes.

7. An automatic pencil comprising, a tube 95 having spiral grooves therein, another tube having spiral grooves of an opposite pitch, a tip secured to one of said tubes, a pair of lead carriers adapted to cooperate with 100 said spiral grooves and another tube forming a guide for said lead carriers, the arrangement being such that either of the lead carriers may be projected or retracted through said tip and at such times the lead 105 will always be in line with the central axis of the tubes.

8. An automatic pencil comprising, a tube having spiral grooves therein, another tube having spiral grooves of an opposite pitch, 110 a tip secured to one of said tubes, a pair of lead carriers adapted to cooperate with said spiral grooves, said lead carriers having offset portions adjacent their lower ends, and another tube having guides therein for said 115 lead carriers, the arrangement being such that either of the lead carriers may be projected or retracted through said tip and at such times the lead will always be in line with the central axis of the tubes.

9. An automatic pencil comprising, a tube having spiral grooves therein, another tube having spiral grooves of an opposite pitch, a tip secured to one of said tubes, a pair of lead carriers adapted to cooperate with said 120

spiral grooves, said lead carriers having offset portions adjacent their lower ends, another tube having guides therein for said lead carriers, and means for interlocking said 5 tubes in relation to each other, the arrangement being such that either of the lead carriers may be projected or retracted through said tip and at such times the lead will always be in line with the central axis of the 10 tubes.

10. An automatic pencil comprising, a tube having spiral grooves therein, another tube having spiral grooves of an opposite pitch, a tip secured to one of said tubes, a pair of 15 lead carriers adapted to cooperate with said spiral grooves, said lead carriers having offset portions adjacent their lower ends, another tube having guides therein for said 20 lead carriers, means for interlocking said tubes in relation to each other, and an outer casing, the arrangement being such that by rotating the tip either of the lead carriers

may be projected or retracted through said tip and at such times the lead will always be in line with the central axis of the tubes. 25

11. An automatic pencil comprising, a tube having spiral grooves therein, another tube having spiral grooves of an opposite pitch, a tip secured to one of said tubes, a pair of lead carriers having pins adapted to operate 30 in said spiral grooves, said lead carriers having offset portions adjacent their lower ends, and another tube having guides therein for said pins on the lead carriers, said spiral grooves being so formed in relation to each 35 other that the guide pins on the lead carriers will turn said lead carriers on their own axes when said lead carriers are starting their downward movement.

In testimony whereof we affix our signatures.

CHARLES H. STOUT.
JUAN CABALLERO.
